UNITED STATES PATENT OFFICE.

EZRA H. WULFF, OF TOLEDO, OHIO.

AUTOMATIC TRAIN-STOP.

1,138,344.

Specification of Letters Patent.

Patented May 4, 1915.

Application filed August 11, 1913. Serial No. 784,138.

To all whom it may concern:

Be it known that I, EZRA H. WULFF, a citizen of the United States, residing at Toledo, in the county of Lucas and State of Ohio, have invented a new and useful Automatic Train-Stop, of which the following is a specification.

The invention relates to improvements in automatic train stops.

- 10 The object of the present invention is to improve the construction of automatic train stops, and to provide a simple, practical and efficient automatic train stop of comparatively inexpensive construction designed for 15 use on steam and various other railways, and adapted to coact with the independent brake valve and the automatic brake valve, and capable of successively operating the same to take up the slack through the action 20 of the independent brake valve prior to applying the automatic brake valve, whereby long trains of cars may be handled without damage either to the railroad equipment or the passengers or contents of the cars. 25 A further object of the invention is to provide an automatic train stop of this character, equipped with a track device adapted to be connected with and operated by signal actuating mechanism, either me- 30 chanical or electro-mechanical, or any other suitable means, whereby it may be operated in connection with block signals either automatic or otherwise to secure a positive compliance with such signals and prevent the 35 wrecks and other damage resulting from a failure to observe or disobedience of such signals.

Another object of the invention is to provide an automatic brake stop provided with 10 mechanism adapted to be actuated by a track device, and capable of producing a slow application of the brakes of the locomotive and tender through the operation of the independent brake valve no matter how 15 high a speed may have been attained by a train or with what force the mechanism of the locomotive contacts with the track device, whereby the air will be handled as properly as when the brakes are operated 20 by a careful engineman.

Furthermore, the invention has for its object to provide a construction adapted when an engineman is attending properly to his engine and to the signals or other orders 25 to permit him to operate the independent brake valve and the automatic brake valve

without the same being affected by the automatic train stop.

With these and other objects in view, the invention consists in the construction and 60 novel combination of parts hereinafter fully described, illustrated in the accompanying drawings, and pointed out in the claims hereto appended; it being understood that various changes in the form, proportion, 65 size and minor details of construction, within the scope of the claims, may be resorted to without departing from the spirit or sacrificing any of the advantages of the 70 invention.

In the drawings: Figure 1 is an elevation partly in section of an automatic train stop, constructed in accordance with this invention, portions of a locomotive being shown. Fig. 2 is a longitudinal sectional view, taken 75 substantially on the line 2—2 of Fig. 1. Fig. 3 is a perspective view of the track device, shown applied to a portion of the track. Fig. 4 is an elevation of a portion of the locomotive mechanism, illustrating the 80 arrangement of the piston actuating cross head with relation to the independent and automatic valves. Fig. 5 is a plan view of the same. Fig. 6 is a detail sectional view of the independent brake valve attachment. 85 Fig. 7 is a detail perspective view of a portion of the cross head. Fig. 8 is a vertical sectional view of the same. Fig. 9 is a detail elevation of a portion of the cross head, 90 illustrating the construction of the gear to which the valve actuating arm is pivoted. Fig. 10 is an elevation of the upper portion of the vertically movable plunger bar, the 95 hinged upper section being swung downwardly from its operative position. Fig. 11 is a sectional view, illustrating the construction of the cylinder and the piston for actuating the cross head. Fig. 12 is a detail 100 sectional view, illustrating the construction of the guide for the transverse lever of the track device. Fig. 13 is a detail sectional view, illustrating the construction of the connection between the transverse lever and the contact bar of the track device. Fig. 14 is a detail perspective view of one end of the 105 contact bar. Fig. 15 is a plan view of the flexible shoe.

Like numerals of reference designate corresponding parts in all the figures of the drawings.

In the accompanying drawings in which is illustrated the preferred embodiment of

the invention, 1 designates a contact bar or member, designed to extend longitudinally of a track between the rails thereof and tapered at an intermediate point toward each end to provide an oppositely inclined upper contact face 2, adapted to actuate a vertically movable plunger bar 3 of valve actuating mechanism carried by a locomotive or the like. The contact bar or member, 10 which may be made of any suitable material, is preferably stamped or otherwise formed of malleable metal to provide a hollow bar or member, consisting of spaced sides and a connecting top portion, as clearly illustrated in Fig. 14 of the drawings. The lower edges of the sides of the contact bar are straight and the said bar, which is preferably arranged upon a base plate 4, is pivoted at one end by a transverse pin 5 or other suitable 20 device between a pair of ears 6, projecting upwardly from the base plate, which is mounted upon the cross ties 7 of the track. The base plate, which is suitably secured to the cross ties 7, is provided with a plurality of upwardly projecting lugs 8 presenting inner vertical faces to the sides of the contact bar and adapted to guide the same in the upward and downward movement thereof. The lugs 8, which are preferably beveled, as shown, may be of any desired number, and the contact bar is provided at its other end with a depending arm 9 having a slot 10 through which passes a relatively fixed fastening device 11, which limits the 30 upward movement of the contact bar. The depending arm 9 is arranged at the side face of one of the cross ties, and the fastening device 11 is preferably embedded in such cross tie, but any other suitable projecting means may be employed for operating in the slot of the arm to limit the upward movement of the contact bar 1.

The contact bar 1 is elevated to its engaging position by a substantially oblong block 12 having a rounded lower end 13 and pivoted thereat in a recess 14 of a supporting plate by a horizontal pin 15, or other suitable fastening device. The block 12, which is rounded at one of its upper edges at 16, 40 is adapted to swing upwardly to the position illustrated in Fig. 13 of the drawings. This movement carries the rounded portion 16 into contact with a bottom plate 17 of the contact bar, which when elevated rests upon the upper edge or face of the block 12. The plate 17 is suitably secured to the sides of the hollow contact bar, and it presents a flat lower face to coact with the pivoted block 12. The pivoted block 12 is connected with 50 a transverse lever 18 by links 19 and 20, secured to the block 12 and the lever 18 in recesses 21 and 22 thereof by pins 23 and 24 or other suitable fastening devices, which span the said recesses 21 and 22. This provides a loose connection between the trans-

verse lever and the block, which is positively swung upwardly by the said lever. The block when swung upwardly to a vertical position constitutes a practically rigid support for the contact member, which is thereby adapted to positively actuate the plunger bar no matter how fast a train may be moving. The supporting plate, which is constructed of sheet steel or other suitable material, is stamped or otherwise formed to provide the recess 13, and it has a tubular housing 25 receiving a coiled spring 26, which is adapted to be compressed by the upward movement of the block, whereby the latter will be positively swung downwardly and outwardly to lower the contact bar when the transverse lever is depressed. The block is provided with a projection 12^a, extending into the outer end of the coiled spring 26 and arranged to be engaged by the same in the outward or downward movement of the pivoted block. This projection insures a complete movement of the block and is adapted to prevent the spring from binding or cramping in the upward or inward movement of the block. The transverse lever, which has its inner portion arranged beneath the contact bar 1, extends outwardly to a point beyond the adjacent rail 27, and it is fulcrumed at an intermediate point on a bolt 28 or other suitable fastening device. The inner end of the transverse lever operates in a vertical guide 29, consisting preferably of an oblong loop suitably mounted on the adjacent cross tie. The outer end of the transverse lever is connected by a link 30 with the lower arm 31 of a signal and in the accompanying illustration is designed to be operated in conjunction with the signal by any suitable means either automatic or manual from a tower or other operating station. In order to enable the track device to be easily operated by comparatively little power to elevate the contact bar, the transverse lever is equipped with a weight 32, 110 adjustably mounted on the outer arm of the transverse lever and adapted to counterbalance or partially counterbalance the track device. The link or bar 30 is pivoted at its lower end to the outer end of the transverse lever 18, and at its upper end to the lower arm 31 of the signal, but any other suitable connecting means may, of course, be employed to adapt the track device to the particular operating mechanism with which it 120 is to be used. The transverse lever preferably occupies an inclined position, as illustrated in dotted lines at the left hand side of Fig. 1 of the drawings when the contact bar is lowered or in an inoperative position, 125 and the outer arm of the transverse lever is swung downwardly to raise the inner arm thereof and thereby elevate the contact bar to the position illustrated at the right hand side of Fig. 1 of the drawings. 130

No claim is made in the present application to the particular construction of the track device.

The vertically movable plunger bar 3, 5 which has its upper end located beneath and adapted to actuate the handle 33 of a valve 34, extends through the deck 35 of a locomotive and into the cab thereof and is mounted in suitable guides 36 and 37, located above and below the deck 35. These guides may be of any preferred construction, and the lower guide, which is open at the back, carries a pin or projection 38, which 10 operates in a slot 39 of the plunger bar and limits the vertical movement thereof to prevent the said bar from being thrown too far through contact with the track device. The plunger bar, which is urged downwardly by a coiled spring 40, is provided with an adjustable upper section 41, connected at its lower end by a suitable hinge 42 with the lower or body portion of the plunger bar. The lower body portion of the plunger bar is provided at the hinged end of the section 15 41 with a projecting portion 43, located at the opposite side of the bar to that which the hinge 42 is arranged and adapted to form a stop for limiting the upward swing of the section 41 to assist in maintaining the 20 same in a perpendicular position for operating the valve 34. The lower or body portion of the plunger bar carries a relatively fixed substantially quadrant-shaped plate 44, having upper and lower notches 45 and 46 25 adapted to be engaged by a spring actuated dog or detent 47, which is connected with a latch lever 48. The latch lever 48 is mounted on a suitable support 49 consisting of an inclined rod or bar secured at its lower terminal to the hinged section 41 and provided at its upper end with an arm or portion extending from the inclined rod or bar substantially at right angles to the same and secured to the said section 41 adjacent to the 30 upper end thereof. The support 49 offsets the latch lever from the hinged section 41 and enables the said latch lever to be substantially grasped by the engineman when it is desired to disengage the spring actuated dog or detent from the plate 42 to swing the hinged section 41 either upwardly or downwardly. The hinged section 41 is adapted to be swung downwardly to render the plunger bar inoperative when through proper 35 requirements of the service it is necessary to render the automatic stop inoperative. When the upper section 41 of the plunger bar is swung downwardly out of the path of the handle 33 of the valve 34, the plunger 40 bar is moved upwardly by a lever 50 to elevate a roller or wheel 51 above the plane of the contact bar when the latter is in its set or operative position. The roller or wheel 51 is preferably mounted in a fork or bifurcation 52 of the lower end of the plunger 45 bar, and in order to prevent injury to the plunger bar through contact with the bar or member 1 when a train is traveling at a high rate of speed, the automatic stop is equipped with a flexible shoe 53, preferably 50 consisting of a steel strap and extending longitudinally of a locomotive to a point in advance and in rear of the plunger bar and secured at its front end 54 to a horizontal arm 55 of a relatively fixed supporting bracket 56. The supporting bracket 56 is mounted on the locomotive at a sufficient elevation to prevent it from coming in contact with any portion of the track device, and the rear end of the flexible shoe is provided with an opening 57 and is slidably connected with an adjustable supporting bracket 58 by a vertical rod or pin 59. The vertical rod or pin 59 is secured at its ends to spaced upper and lower arms 60 and 61, which project from the lower portion of the adjustable bracket 58. The rear end of the flexible shoe, which is carried by the adjustable bracket, is yieldably held against the lower face of the lower arm 61 by a coiled spring 62, disposed on the 60 rod or pin 59 and interposed between the upper arm 60 and the rear end of the flexible shoe. The flexible shoe is adapted to soften the blows incident to the contact of the plunger bar with the contact arm, and it enables an easy operation of the valve actuating mechanism to be effected without injuring the same. The adjustable bracket 58 consists of the said spaced arms and a vertical stem, slidably mounted in a suitable 65 guide 63 and extending through the deck 35 and connected by a short link 64 with one arm of an operating lever 65. The operating lever 65, which is fulcrumed at an intermediate point on a standard 66 by a pin or bolt 67, is adapted to be oscillated to raise and lower the adjustable bracket 58, and it is secured in its adjustment by a spring actuated dog or detent 68, controlled by a latch lever 69 and arranged to engage a notched segment 70, which is preferably formed integral with the standard 66. The bracket 58 is adapted to be raised to elevate the shoe above the plane of the track device when the plunger bar is elevated. The plunger bar is elevated by means of the lever 50 suitably fulcrumed at one end and extending beneath a pin or projection 71 of the plunger bar and arranged to engage the teeth of the ratchet bar 72. The ratchet bar, which is arcuate, is 75 suitably mounted on the boiler 73 or other convenient portion of the locomotive, and it is adapted to be swung upwardly from the position shown in Fig. 1 to engage the pin 71 and elevate the plunger bar. When the plunger bar is actuated through contact with the bar or member 1 of the track device, it moves upwardly independently of the lever 50, and the spring 40 draws the plunger bar downwardly after an operation thereof. 80

The lower end of the pincher bar and the flexible slot are naturally maintained in position to be engaged by the contact bar of the track device when the latter is in its raised or set position, and when it comes in contact with the same, it is moved upwardly and swings the handle 33 of the valve 31 generally.

The valve 31, which may be of any preferred construction, is designed to do the same as the independent brake valve of the Westinghouse No. 4, 12, 2 locomotive brake equipment, and the purpose of the valve is to move the handle of the valve in a position corresponding with the degree of the compression of the said independent valve. The valve 31 is connected by suitable piping connections 73 with an air cylinder 77, which is also by suitable pipe connections 78 connected with a cylinder 77, whereby it is desired to move air from the cylinder 77 from the cylinder 73 by means of the piston 79, and of the bellows mechanism, so that the operating of the cylinder 77 and the piston 79, and of the 100 valve 31, will effect a reduction in the pressure of the air or directly produce an application of the brakes, a fluid pressure being obtained from any suitable cylinder 77, 105 supply cylinder 77, or the cylinder 77, connections for reducing the pressure of the mechanism of the locomotive, or from a 110 valve 73, or a cylinder 77, or from an ordinary cylinder, or from any suitable 115 pipe connection 78, or from any suitable 120 connection between the cylinder 77 and the cylinder 73, of the apparatus, so that the cylinder 77, valve and the cylinder 77, will produce a proper amount of air at the cylinder 77, 125 to be supplied to the cylinder 77, or to 130 operating a piston 79. The piston 79, or cylinder 77, tends to move air from the cylinder 77, or cylinder 73, independently of the cylinder 77, or cylinder 73, adopted to move the piston 79, or cylinder 77, 135 moved distance, against the action of the spring 81, such a movement of the piston 79, or cylinder 77, being arrested by a second or safety spring 82. The first or initial movement of the piston operates the valve 31, which valve 140 valve 83 of the brake equipment, and the second movement, which movement the shock has been taken out of the piston, or 145 action of the valve, but the second movement effects an operation of the valve 31, or piston 79, 150 valve 81, and a setting up of the same may be made without reference to the train. This operation of the independent and automatic brake valve, respectively, is 155 adapted to bring a train to a standstill in the same manner as when the brakes are applied by a skilful and careful engineer. The springs 81 and 82 are disposed on the piston rod and are interposed between the head of the piston and the cylinder at the 160

and opposite thereof, which the air is to be admitted. The open portion of the cylinder through which the piston rod extends is preferably tapered, as shown, but the cylinder may be of any preferred construction, as will be readily understood. The piston rod is sealed and held up just a story inclosed by a sleeve, all mounted in a threaded portion of the cylinder at the outlet or front end thereof, and having an inverted tapered surface, or in a flared position, which may be created by a longitudinal slot set in a sleeve, so as to hold the piston rod, and a sealing spring made, of course, of cork, or cork, or any other flexible and resilient material, and which is interposed between the piston and cylinder, so as to completely seal off the cylinder. This will prevent any escape of steam, and the piston rod will be turned so that it will be exposed to steam, either to the front end, or to the rear end, as may be desired.

and the engineer can be sure that the signals are being observed and that the engineer is qualified to handle the trains. In 116 cases the engineer has been given notice of his inexperience. This notice has been received by 116 engineers. The engineer has been given a copy of the code of rules and regulations, or the signals, the first 118 is printed for a first class and suitable for use in railroads. The 116th copy of the code of rules and regulations is a copy for the engineer of the first 118 to print a copy and to keep the same. It is of value to the engineer to operate. When the engineer is 116 and is properly watching the signals 120 and attending to his locomotive, he may 120 cause the brake valves to meet the requirement, and comply with the signals, but if any accident should happen to the engineer or should he through any cause whatever fail to operate the brakes in response to the signals, the automatic stop will perform its function. The printed arm or

member 88 is rigidly secured in projecting operative position by a spring catch 91, consisting of a piece of resilient material bent to form an approximately U-shaped loop or 5 bend and an inclined attaching portion 92. The U-shaped loop or bend consists of upper and lower horizontal sides and a connecting portion, the upper side extending through a perforation 93 of the arm or projection 10 and adapted to engage either one of a pair of perforations 94 and 95 to lock the projecting arm or member 88 in either its operative or inoperative position. The lower side of the U-shaped loop or bend extends 15 through a perforation 96, and the attaching portion 92 is located at the opposite side of the arm from the connecting portion 91, which constitutes a convenient handle for enabling the catch to be readily grasped to 20 release the arm 88 to permit the same to be swung upwardly or downwardly. The pivoted arm or member 88 is provided at the top opposite the pivot with an upwardly projecting finger 97, which extends beneath 25 a horizontal finger 98 arranged in spaced relation with the cross head and adapted to coact with the finger 97 to maintain the projecting arm or member firm and steady in its operative position. The finger 98 is angularly bent at an intermediate point to form 30 an attaching portion 99, which is secured to the cross head.

The independent brake valve is equipped with an attachment consisting of an approximately horizontal operating arm 100, arranged in the path of one of the projecting arms or members of the cross head and yieldably connected with the handle 101 of the independent brake valve by an arcuate 35 rod 102 and a coiled spring 103. The spring 103 is mounted in a housing 104 of a plate or support 105, which is rigid with the stem 106 of the independent brake valve. The plate or support 105 may be rigidly connected with the handle 101 in any other suitable manner, and the rod 102, which extends through the housing, is pivoted at its inner or front end 106^a to the arm 100, which is pivotally mounted at its inner end on the 40 stem 106 (see Fig. 6) and movable independently of the handle 101 of the independent brake valve. The curved rod 102, which is provided at its outer end with a stop nut 107, carries an adjustable nut 108 or other suitable means for engaging the 45 spring 103, which is interposed between the nut 108 and the rear end of the housing 104. The spring 103 is of considerably less strength than the spring (not shown) constituting a part of the independent brake 50 valve and adapted to yieldably hold the handle in position for a slow application of the brakes of the engine and tender. With the independent brake valve, the handle 101 may 55 be readily moved by a slight pressure, say about one pound, from the running position to the slow application position, and the independent valve, as constructed, requires a relatively heavy pull to move it from a slow application position to a quick application position. As the spring 103 is of considerably less strength than the spring, which holds the handle 101 in the slow application position of the valve, a further movement of the cross head will operate to 60 compress the spring 103 within the housing and pass the arm 100 without moving the handle 101 from the slow application position. In practice when the plunger bar 3 is moved upwardly by the track device and the valve 34 opened to permit air to pass into the cylinder 77, a sufficient pressure will be admitted to the said cylinder 77 to 65 compress the spring 81 and effect a movement of the cross head 85 sufficient to carry the handle 101 to the slow application position. This is done by one of the projecting arms or member 88, which engages the arm 100, the spring 103 being sufficiently stiff to carry the handle 101 to such position without material compression. While the pressure is accumulating within the cylinder 77 sufficient to overcome the second spring 82 70 thereof, the brakes of the engine and tender are applied and the slack taken out of the train. As soon as the pressure within the cylinder becomes sufficient to compress the spring 82, a further movement is imparted to the piston and the other projecting arm or portion of the cross head is carried into 75 direct engagement with the handle 109 of the automatic brake valve, which is carried to a service position.

The automatic stop may be duplicated on a locomotive as well as the track device, as 80 illustrated in Fig. 1 of the drawings, the valve 34 being connected with the pipe connections 74 and 76 and operating in a manner similar to the valve 34 heretofore described. The duplication of the automatic stop will be found particularly advantageous 85 for adapting the engine for running either backward or forward, and a greater range of signaling will be possible by employing two sets of the automatic train stop mechanism. One set may be utilized when the train is traveling in one direction and the other set while the train is traveling in the opposite direction, and when the valve actuating mechanism at one side of a locomotive 90 is in operation that at the other side will be arranged in an inoperative position. This will adapt the locomotive for use on a single track.

When the automatic stop is employed on 95 an electric street car or a similar conveyance having only a single motorman's valve, the plunger bar may be arranged either to

directly operate the motorcyclist's controls. A duplicate valve switch dispensing with the cross-hand fuel lever is often used. There are numerous ways to control the engine's starting sequence.

5 months.

THE BOSTONIAN, OR, THE AMERICAN JOURNAL OF LITERATURE AND SCIENCE, VOLUME 1, NO. 1, APRIL 1837.

35 patients with a mean age of 50 years. The patients were assigned to a control group (n = 18) and a treatment group (n = 17). The treatment group received a 100 mg dose of ibuprofen orally every 8 hours for 10 days. The control group received a placebo. The patients were evaluated at baseline and at days 1, 5, and 10. The primary outcome measure was the change in pain score from baseline to day 10. The secondary outcome measures included the change in functional status, the change in quality of life, and the change in sleep quality.

the piston. The piston and cylinder are arranged to

to operate the independent and automatic brake valves.

12. The combination with a locomotive brake equipment having independent and automatic brake valves, the independent brake valve being located in advance of the automatic brake valve, of an automatic train stop comprising a track device, and mechanism carried by the locomotive and arranged to be operated by the track device, said mechanism including a cylinder having a piston, and a cross head provided with spaced projecting arms arranged to operate the independent and automatic brake valves, said arms being movably mounted and adapted to be arranged in and out of operative position.

13. The combination with a locomotive brake equipment having independent and automatic brake valves, the independent brake valve being located in advance of the automatic brake valve, of an automatic train stop comprising a track device, and mechanism carried by the locomotive and arranged to be operated by the track device, said mechanism including a cylinder having a piston, a cross head provided with spaced projecting arms pivotally mounted and arranged to operate the independent and automatic brake valves, said arms being adapted to be swung into and out of operative position, and catches for locking the arms in either position.

14. The combination with a locomotive brake equipment having independent and automatic brake valves, the independent brake valve being located in advance of the automatic brake valve, of an automatic train stop comprising a track device, and mechanism carried by the locomotive and arranged to be operated by the track device, said mechanism including a cylinder having a piston, a cross head provided with spaced projecting arms arranged to operate the independent and automatic brake valves and movable into and out of operative position, and resilient catches mounted on the arms and having projecting loops or handles and arranged to lock the arms in either position.

15. The combination with a locomotive brake equipment having independent and automatic brake valves, the independent brake valve being located in advance of the automatic brake valve, of an automatic train stop comprising a track device, and mechanism carried by the locomotive and arranged to be operated by the track device, said mechanism including a cylinder having a piston, a cross head provided with spaced projecting pivotally mounted arms arranged to operate the independent and automatic brake valves and adapted to swing into and out of operative position, means for locking the pivoted arms in either position, and coacting fingers mounted on the

cross head and on the arms for holding the latter firmly in operative position.

16. The combination with a locomotive brake equipment having independent and automatic brake valves, the independent 70 brake valve being located in advance of the automatic brake valve, of an automatic train stop comprising a track device, and mechanism carried by the locomotive and arranged to be operated by the track device, 75 said mechanism including a cylinder having a piston, means yieldably connected with the handle of the independent brake valve and adapted when actuated to move the said handle to a slow application, and means 80 carried by the said piston for actuating the yieldable means of the independent brake valve and for operating the automatic brake valve.

17. The combination with a locomotive 85 brake equipment having independent and automatic brake valves, the independent brake valve being located in advance of the automatic brake valve, of an automatic train stop comprising a track device, and 90 mechanism carried by the locomotive and arranged to be operated by the track device, said mechanism including a cylinder having a piston, an arm yieldably connected with the handle of the independent brake valve 95 and adapted when actuated to move the said handle to a slow application position, said yieldable means permitting the arm to move independently of the handle to prevent further application of the independent 100 brake valve, and means carried by the piston for oscillating said arm and for operating the automatic brake valve.

18. The combination with a locomotive brake equipment having independent and 105 automatic brake valves, the independent brake valve being located in advance of the automatic brake valve, of an automatic train stop comprising a track device, and mechanism carried by the locomotive and 110 arranged to be operated by the track device, said mechanism including a cylinder having a piston, an arm pivotally mounted on the independent brake valve, yieldable means for connecting the arm with the handle of the brake valve consisting of a spring; and a rod engaging the spring, said arm being adapted when actuated to move the handle of the independent brake valve to a slow 115 application position, and means carried by the piston for actuating the arm and for operating the automatic brake valve.

19. The combination with a locomotive brake equipment having independent and automatic brake valves, the independent 125 brake valve being located in advance of the automatic brake valve, of an automatic train stop comprising a track device, and mechanism carried by the locomotive and arranged to be operated by the track device, said 130

mechanism including a cylinder having a piston, an arm pivoted on the independent brake valve, a support connected with the handle of the independent brake valve and having a housing, a spring mounted in the housing, a curved rail connected with the arm and provided with means for engaging with snap-spring feet of the said spring, said support being adapted to move in response to the cylinder applying pressure to the piston, the said rail being connected with the handle of the independent brake valve, and means carried by the piston for operating the secondary and for operating the independent brake valve.

55. Starting equipment with a lever having a handle, a piston of an independent and automatic brake valve, an intermediate track stop connecting a track device and the mechanism operated on the locomotive and arranged to be operated by the track device and including a cylinder having a piston, a device actuated by the piston to operate the said valves, an arm mounted on the independent brake valve, yieldable means for connecting the arm with the handle of the independent brake valve and adapted, when actuated, to move the said handle to a new application position, said yieldable means permitting the arm to move independently of the handle to permit further application of the independent brake valve, and means carried by the piston for moving the said arm.

56. The combination with a locomotive brake equipment having independent and automatic brake valves, the independent brake valve being located in advance of the automatic brake valve, of an automatic starting equipment comprising a track device, a piston mounted on the locomotive and actuated by the track device, and said track device including a cylinder having a piston, a lever carried by the piston and movable toward from the said valves and arranged to successively operate the said and normal stop means successively in opposition to the said independent brake valve, and for connecting the said lever to the said normal stop means.

57. The combination with a locomotive brake equipment having independent and automatic brake valves, the independent brake valve being located in advance of the automatic brake valve, of an automatic starting equipment including a cylinder having a piston pivoted with means for operating the said valves, and springs arranged

to successively resist the movement of the piston and also to react to produce an increased resistance to cause an interval of time to elapse between the operation of the independent and automatic brake valves.

58. The combination of brake actuating mechanism including a valve having an arm or handle, a plunger bar arranged to engage and move the said valve, and a handle to operate the valve, said plunger bar having a movable section or slot adapted to be arranged in an operative position to prevent an operation of the said valve, and a track device having a contact member for actuating the plunger bar.

59. The combination of brake actuating mechanism including a valve having a handle, a track device having a contact member, and a plunger bar adapted to be operated by the contact member of the track device and arranged to engage and move the handle of the said valve, said plunger bar having a pivoted section or portion adapted to be moved into and out of operative position.

60. The combination of brake actuating mechanism including a valve having an arm or handle, a plunger bar arranged to engage and move the said arm or handle to operate the valve, and plunger bar being provided with a pivoted upper section arranged to be moved into and out of operative position, and means for locking the said section.

61. The combination of brake actuating mechanism including a valve having an arm or handle, a plunger bar adapted to be actuated by the contact member of the track device and arranged to move the arm or handle of the valve and having a movable portion adapted to be arranged in and out of operative position, and means for supporting the plunger bar in an elevated position beyond the place of the contact member.

62. The combination of brake actuating mechanism including a valve having an arm or handle, a plunger bar adapted to be arranged to the contact member of the track device and arranged to move the arm or handle of the valve and having a movable portion arranged to be arranged in and out of operative position, and a lever arranged to support the plunger bar in such elevated position.

63. The combination of brake actuating mechanism including a valve having an arm or handle, a plunger bar adapted to be actuated by the contact member of the track device and arranged to move the arm or handle of the valve and having a movable portion arranged to be arranged in and out of operative position, a lever arranged to

- lift the plunger bar above the plane of the contact member of the track device, means for engaging the lever to support the plunger bar in such elevated position, and means connected with the plunger bar for urging the same downwardly.
29. In an automatic train stop, the combination with a valve, of valve actuating mechanism including a track device having a contact member, a plunger bar arranged to be actuated by the track device for operating the said valve, and a shoe consisting of a strip of flexible metal extending beneath the plunger bar and arranged to be interposed between the same and the contact member of the track device to prevent injury to the former, said flexible strip having inclined front and rear portions, and means located in advance and in rear of the plunger bar and connected with the ends of the flexible strip for supporting the latter.
30. In an automatic train stop, the combination of valve actuated mechanism including a valve, a track device having a contact member, a plunger bar arranged to be actuated by the track device for operating the said valve, a shoe consisting of a strip of flexible metal extending beneath the plunger bar and arranged to be interposed between the same and the contact member of the track device to prevent injury to the former, and means located in advance and in rear of the plunger bar for supporting the flexible strip.
31. In an automatic train stop, the combination of valve actuated mechanism including a valve, a track device having a contact member, a plunger bar arranged to be actuated by the track device for operating the said valve, a strip of flexible material extending beneath the plunger bar and arranged to be interposed between the same and the said contact member, and means for supporting the flexible strip in advance and in rear of the plunger bar, one of the supporting means being adjustable upwardly and downwardly.
32. In an automatic train stop, the combination of valve actuated mechanism including a valve, a track device having a contact member, a plunger bar arranged to be actuated by the track device for operating the said valve, a strip of flexible material extending beneath the plunger bar and arranged to be interposed between the same and the said contact member, and means for supporting the flexible strip in advance and in rear of the plunger bar, one of the supporting means consisting of a vertically movable bracket adapted to raise the flexible strip to an inoperative position, and means for securing the bracket in its adjustment.
33. In an automatic train stop, the combination of valve actuated mechanism including a valve, a track device having a contact member, a plunger bar arranged to be actuated by the track device for operating the said valve, a strip of flexible material extending beneath the plunger bar and adapted to be interposed between the same and the contact member, and means for supporting the flexible strip including an adjustable bracket having spaced arms, a guide connecting the arms and receiving the flexible strip, and a spring carried by the guide for urging the flexible strip downwardly.

In testimony that I claim the foregoing as my own I have hereto affixed by signature in the presence of two witnesses.

EZRA H. WULFF.
